UNITED STATES PATENT OFFICE

ADOLPH J. KETTERLING, OF ZEELAND, NORTH DAKOTA

GRAIN DOOR FOR BOX CARS

Application filed April 21, 1931. Serial No. 531,755.

This invention relates to a grain door for a box car, and has for one of its objects to provide a door of this character embodying lower, upper and intermediate sections which shall be mounted for independent horizontal movement into opened or closed position, which shall be provided at their adjacent horizontal edges with means adapted when the sections are in closed position to prevent the sections are in closed position to prevent the passage therebetween of grain, and which shall embody a construction adapted to permit them to be made of comparatively light sheet metal and yet be of sufficient strength as to prevent them from being distorted.

15 The invention has for a further object to provide means for slidably supporting the door sections which shall embody horizontal tracks secured to the car and of triangular formation in cross section, and slides similar in cross section to and mounted within the tracks and having the door sections secured thereto.

The invention has for a further object to provide means for housing the door sections supporting means in such manner as to prevent the grain from interfering with the movement of the door sections into opened or closed position, this means having an open end through which the door sections move and a flap cooperating with the door sections to prevent grain from entering the same by way of said end thereof.

35 The invention has for a further object to provide a door, supporting means for the door, and housing means for the door which shall be simple, durable and capable of being manufactured at low cost.

With the foregoing and other objects in view, the nature of which will appear as the 40 description proceeds, the invention consists in the construction, combination and arrangement of parts hereinafter fully described and claimed, and illustrated in the accompanying drawings, wherein:—

45 Figure 1 is a view partly in vertical section and partly in elevation illustrating the grain door applied to a box car.

50 Figure 2 is a sectional view taken on the horizontal plane indicated by the line 2—2 of Figure 1.

Figure 3 is a sectional view taken on the vertical plane indicated by the line 3—3 of Figure 1.

Figure 4 is a sectional view on an enlarged scale taken on the horizontal plane indicated by the line 4—4 of Figure 1.

Figure 5 is a sectional view taken on the vertical plane indicated by the line 5—5 of Figure 1.

Figure 6 is a sectional view taken on the vertical plane indicated by the line 6—6 of Figure 1.

Figure 7 is a sectional view taken on the horizontal plane indicated by the line 7—7 of Figure 6.

Figure 8 is a sectional view taken on the vertical plane indicated by the line 8—8 of Figure 1.

Figure 9 is a sectional view taken on the vertical plane indicated by the line 9—9 of Figure 1, and

Figure 10 is a sectional view taken on the vertical plane indicated by the line 10—10 of Figure 2.

Referring in detail to the drawings, 1 designates the bottom, 2 one of the sides, and 3 the top of a box car of well-known construction. 4 designates one of the door openings of the car, and 5 and 6 designate posts at opposite sides of the door opening. A plate 7 arranged within the car and in parallel relation to the side 2 thereof, cooperates with the side to provide a housing 8 which is of greater length than the width of the door opening 4 and which has an open end 9 located near the door post 5. The plate 7 is corrugated longitudinally, as at 10, and its lower edge rests upon the bottom 1 of the car to effect the closing of the lower side of the housing 8. The plate 7 is provided at its upper edge with a flange 11 which extends therefrom in the direction of and contacts with the side 2 of the car, the flange closing the upper side of the housing 8. The plate 7 is reinforced and supported in upright position by standards or studdings 12, 13 and 14. The standard or studding 12 is located between the inner end of the plate 7 and the side 2 of the car and serves to close the corresponding end of the housing 8. The stand-

100

ard or studding 12 is provided with a vertical flange 12a secured, as at 15, to the side 2 of the car, and it is provided with a vertical flange 12b to which the plate 7 is secured, as at 16. The standard or studding 12 is provided with a horizontal flange 12c which is secured, as at 17, to the floor 1 of the car. The standard or studding 13 which is located centrally between and at the inner side of the plate 7, is of triangular formation in horizontal section and is provided at its lower end with a horizontal flange 13a which is secured, as at 18, to the floor 1 of the car. The standard or studding 13 is provided with an angular upper end 13b which overlies the flange 11 of the plate 7 and is secured, as at 19, to the side 2 of the car.

The standard or studding 14 which is located at the outer end and inwardly of the plate 7, is of triangular formation in cross section, and is provided at its lower end with a horizontal flange 14a secured, as at 20, to the floor 1 of the car. The upper end of the standard or studding 14 is of angular formation, overlies the flange 11 of the plate 7, and is secured, as at 21, to the side 2 of the car.

Horizontal tracks 22 of substantial triangular formation in cross section extend from the door post 5 to the inner or closed end of the housing 8, and the greater portions thereof are located wholly within the housing. The tracks 22 are secured, as at 23, to the door post 5, and as at 24, to the standard or studding 12. The tracks 22 are spaced from the plate 7, and the open sides 22a thereof face the plate. The inner end portions of the upper and lower sides 22b of the tracks 22 are cut away, as at 25, for the purpose to be presently set forth. Slides 26 which are similar in cross section to the tracks 22 are mounted in the tracks for endwise movement with respect thereto.

The door comprises a lower section 27, an upper section 28 and an intermediate section 29 which are equal in length and which are greater in length than the width of the door opening 4. The door section 27 is of greater height than the door section 29, and the door section 29 is of greater height than the door section 28. The door section 27 is secured to four of the slides 26, the door section 28 is secured to two of the slides, and the door section 29 is secured to two of the slides, the slides and tracks 22 supporting the door sections for independent horizontal movement into closed or opened position. The door sections 27, 28 and 29 are provided with longitudinal corrugations 30, 31 and 32, respectively, the corrugations being spaced from the horizontal vertical edges of the door sections to provide the door sections with smooth marginal portions.

The door section 27 rests at its lower edge upon the floor 1 of the car, the door section 29

is provided at its lower edge with an inwardly offset and downwardly extending flange 33 contacting with the upper edge portion of the door section 27, and the door section 28 is provided at its lower edge with an inwardly offset and downwardly extending flange 34 contacting with the upper edge portion of the door section 29, to prevent the grain from escaping from the car when the door sections are in closed position.

The door sections 27, 28 and 29 are located between the plate 7 and tracks 22, and are greater in length than the plate. When the door sections 27, 28 and 29 are in closed position their inner smooth marginal edge portions extend into the open lower outer end of the housing 8, and when the door sections are in opened position their outer smooth marginal edge portions extend beyond the open end of the housing, as shown in Figures 2 and 4, respectively. The tracks 22 extend beyond the open or outer end of the housing 8. A flap 35 and a filler 36 cooperate with the inner and outer edge portions of the door sections 27, 28 and 29 and the outer end portions of the tracks 22 to effect the closure of the outer end of the housing 8, when the door sections are in opened or closed position. The flap 35 is equal in height to the housing 8 and comprises sections 35a, 35b and 35c which are hinged, as at 37, to the standard or studding 14. The flap sections 35a, 35b and 35c are similar in height to the door sections 27, 29 and 28, and the free vertical edges of the flap sections contact with the inner end portions of the door sections when the latter are in closed position and contact with the outer end portions of the door sections when the latter are in opened position.

Coil springs 38 secured to the standard or studding 14 and to the flap sections 35a, 35b and 35c yieldingly maintain the free edges of the flap sections in contact with the door sections 27, 28 and 29. The flap sections 35a, 35b and 35c are also employed for the purpose of latching the door sections 27, 28 and 29 in opened or closed position, and to permit this to be done the flap sections are provided at their free edges with lugs or ears 39, and the door sections are provided near their inner edge portions with pins 41. When the door sections 27, 28 and 29 are in closed position the ears 39 of the flap sections 35a, 35b and 35c engage the pins 40, as shown in Figure 2, and when the door sections are in opened position the ears engage the pins 41, as shown in Figure 4, the ears being held in engagement with the pins by the springs 38. The door sections 27, 28 and 29 are provided near their outer ends with handles 42 to permit them to be conveniently moved into closed or opened position, and when it is desired to move the door sections into either of these positions, it is only necessary to swing the flap sections 35a, 35b and 35c in a direction to carry the

ears 39 away from the pins engaged thereby. The filler 36 extends from the door post 5 inwardly beyond the outer end of the plate 7, and extends from the wall 2 of the car to the inner edges of the tracks 22. The flap section 35a is provided at its lower end with a horizontal flange 35d, and the flap section 35c is provided at its upper end with a horizontal flange 35e which extends therefrom in the direction of the door sections 27 and 28, respectively, and which cooperate with these door sections to assist the flap sections in closing the open or outer end of the housing at the inner side of the door sections. The flap sections 35b and 35c are provided with notches 35f and 35g for the reception of the door section flanges 33 and 34, respectively.

If any grain should become lodged in the tracks 22 it will be discharged through the openings 25 of the inner ends of the tracks 22 by the slides 26 during the movement of the door sections 27, 28 and 29 into opened position.

To permit the removal from the housing 8 of any foreign material that may enter the same, the plate 7 is provided near its lower inner corner with a clean-out opening 43 which is closed by a vertical sliding door 44 which is located at the inner side of the plate 7 and which is mounted in guides 44a secured to the plate. The door section 27 is provided near its lower edge with an opening 45 which is closed by a horizontally sliding door 46 mounted in guides 47 secured to the outer side of the door section. The door 46 is provided with a handle 48 which extends through slots 49 in the inner and lower sides of that slide 26 extending across the opening 45. The handle 48 does not project outwardly beyond this slide 26, and in view thereof it will not interfere with the movement of the door section 27 into closed or opened position. The door 46 is opened to permit the grain adjacent the door sections 27, 28 and 29 to flow through the opening 45 of the door section 27 and thus relieve the pressure of the grain against the door sections and enable them to be readily moved into opened position. The door post 6 is provided with keepers or rests 50 which are similar in cross sectional formation to the tracks 22 and which receive the outer ends of the slide 26 when the door sections 27, 28 and 29 are in opened position, the keepers or rests 50 being secured, as at 51, to the door post.

From the foregoing description, taken in connection with the accompanying drawings, it will be understood that the tracks and slides 60 support the door sections for independent horizontal movement, that the housing prevents the grain from interfering with the movements of the door sections, that the flap sections and filler cooperate with the door sections to close the open or outer end of the

housing, and that the flap sections furthermore provide means for latching the door sections when in either closed or opened position. It will be further understood that the pressure of the grain against the door sections 70 may be readily removed and that thereafter the door sections may be readily opened, and that the flap sections may be readily disengaged from the door sections to permit the latter to be closed or opened. All parts 75 of the invention are made of metal. Due to the reinforcing ribs of the plate and door sections and to the supporting standards or studdings for the plate, the plate and door sections may be made of comparatively light 80 sheet metal.

While I have described the principle of the invention, together with the structure which I now consider the preferred embodiment thereof, it is to be understood that the 85 structure shown is merely illustrative and that such changes may be made, when desired, as fall within the scope of the invention as claimed.

I claim:

1. In combination, a box car having a door opening in a side thereof, means located within the car at one side of the door opening and cooperating with the car side to provide a housing open at that end thereof nearest the door opening, tracks supported horizontally within the housing, sets of slides carried by the tracks, door sections having certain ends thereof extending into the housing when in closed position and having their other ends 100 extending beyond the housing when in opened position, means cooperating with the housing and said ends of the door sections to close the open end of the housing, pins carried by the door sections, and elements carried by said means and adapted to engage the pins to secure the door sections in one of said positions.

2. In combination, a box car having a door opening in a side thereof, a door post secured within the car at one side of the door opening, a housing located within the car and having an open end arranged in spaced relation to the door post, horizontal tracks having the greater portions thereof arranged 110 within the housing and the lesser portions thereof projecting through the open end of the housing to the door post, means securing the tracks to the door post and housing, sets of slides mounted on the tracks, door sections secured to the sets of slides and movable into opened or closed position through the open end of the housing, certain of the door sections extending into the housing when in closed position and the other ends of the door sections extending beyond the housing when in opened position, a filler projecting beyond the open end of the housing and surrounding those ends of the tracks located between the door post and housing for contact with the 120

outer sides of the door sections, flaps pivoted to the outer end of the housing for contact with the door sections, and means yieldingly holding the flaps in contact with the door sections.

3. In combination, a box car having a door opening in a side thereof, a door post secured within the car at one side of the door opening, a housing located within the car and having an open end arranged in spaced relation to the door post, horizontal tracks having the greater portions thereof arranged within the housing and the lesser portions thereof projecting through the open end of the housing to the door post, means securing the tracks to the door post and housing, sets of slides mounted on the tracks, door sections secured to the sets of slides and movable into opened or closed position through the open end of the housing, certain of the door sections extending into the housing when in closed position and the other ends of the door sections extending beyond the housing when in opened position, a filler projecting beyond the open end of the housing and surrounding those ends of the tracks located between the door post and housing for contact with the outer sides of the door sections, flaps pivoted to the outer end of the housing for contact with the door sections, pins carried by the door sections, and ears carried by the flaps for engagement with the pins to secure the door sections in one of their positions.

4. In combination, a box car having a door opening in a side thereof, a door post secured within the car at one side of the door opening, a housing located within the car and having an open end arranged in spaced relation to the door post, horizontal tracks having the greater portions thereof arranged within the housing and the lesser portions thereof projecting through the open end of the housing to the door post, means securing the tracks to the door post and housing, sets of slides mounted on the tracks, door sections secured to the sets of slides and movable into opened or closed position through the open end of the housing, certain of the door sections extending into the housing when in closed position and the other ends of the door sections extending beyond the housing when in opened position, a filler projecting beyond the open end of the housing and surrounding those ends of the tracks located between the door post and housing for contact with the outer sides of the door sections, flaps pivoted to the outer end of the housing for contact with the door sections, and means yieldingly holding the flaps in contact with the door sections, a door post located within the car at the opposite side of the door opening, and keepers secured to said last door post for the reception of the portions of the

slides when the door sections are in closed position.

5. In combination, a box car provided in a side thereof with a door opening, a door post located within the car at one side of the door opening, a plate located within the car in spaced parallel relation to the side thereof to provide a housing having an open outer end located near the door post, means closing the upper and lower sides of the housing, a standard closing the inner end of the housing and secured to the side of the car and to the plate, a standard secured to the car and contacting with the inner side of the plate between the ends of the latter, a standard within the car and contacting with the inner side of the plate near the outer end of the latter, sets of slides mounted for movement into opened and closed positions, the door sections having certain of their ends located within the housing when in closed position and having their other ends projecting beyond the open end of the housing when in opened position, tracks having the greater portions thereof located within the housing and having the lesser portions thereof projecting through the open end of the housing to the door post, a filler contacting with the far side door post and with certain ends of the door sections and having the outer ends of the tracks embedded therein, flaps hinged to said last standard and contacting with certain ends of the door sections and cooperating with the filler and door sections to close the open end of the housing, pins secured to the door sections, and ears carried by the flaps and engaged with the pins to secure the door sections in one of said positions.

In testimony whereof I hereunto affix my signature.

ADOLPH J. KETTERLING.
